OFFSET NIPPLE

William E. Kelly, Jersey City, N.J., assignor to The Thomas & Betts Co., Elizabeth, N.J., a corporation of New Jersey

Filed Aug. 31, 1961, Ser. No. 66,572

Term of patent 14 years

(Cl. D91—3)

FIG. 1 is a perspective view of an offset nipple showing my new design;

FIG. 2 is a view in elevation of one end of the offset nipple shown in FIG. 1;

FIG. 3 is a side elevational view of the offset nipple shown in FIG. 1; and

FIG. 4 is a view in elevation of the end of the offset nipple opposite to that shown in FIG. 2.

The side of the offset nipple opposite to that shown in FIG. 3 is a mirror image of that shown in FIG. 3.

I claim:

The ornamental design for an offset nipple, as shown and described.
